CLOSURE LOCK

Rudolph W. Rosberg, Chicago, Ill.

Application May 14, 1942, Serial No. 442,921

1 Claim. (Cl. 70—211)

This invention relates to improvements in a door lock, and refers specifically to a combination padlock and keeper bar which may be secured to the door, such as a door handle or the like, or may be secured adjacent the door, on the door frame, for instance, and be movable across the path in which the door swings.

The objects and advantages of my invention will be apparent from the accompanying drawing and following detailed description.

In the drawing, Fig. 1 is a rear view of an automobile, illustrating my invention in conjunction with the trunk door of an automobile trunk.

Fig. 2 is a sectional view taken on line 2—2 of Fig. 1.

Fig. 3 is a sectional view taken on the line 3—3 of Fig. 2.

Fig. 4 is a sectional view taken on the line 4—4 of Fig. 3.

Although for purposes of description my invention is illustrated in conjunction with an automobile trunk door, it is to be understood that it can be employed in conjunction with any type of door or movable closure.

Referring in detail to the drawing, 1 indicates a conventional automobile having the usual built-in trunk carried at the rear of the vehicle, the trunk being provided with a swingable door 2. The door 2 carries the usual trunk door lock 3 which comprises a lock body structure 4 which is inserted in the trunk door. The body 4 carries a handle 5 in the spindle of which a conventional tumbler mechanism 6 is mounted.

This type of trunk handle and lock is conventional and with slight modifications is standard upon substantially all automobiles. However, this type of lock, although convenient and of good appearance is not very effective as a locking agency. It is a very simple matter, when the lock is locked, for a thief to telescopically slide a pipe or the like along the handle 5 and with the increased leverage thus afforded, turn the handle 5 and strip or shear the retaining mechanism, usually a comparatively small pin, in the lock. As will be hereinafter more fully appreciated by employing my lock structure in combination with the handle 5, this practice is effectively prevented.

My lock structure, designated in its entirety as 7, is adapted to be positioned upon the trunk door 2 adjacent the conventional lock 3. The lock structure 7 comprises essentially two body portions 8 and 9 and a U-shaped retaining member 10. The body portions may be secured together and secured to the wall 11 of the trunk door 2

by means of bolts 12 which are preferably of the "carriage bolt" type having plain or unslotted heads 13 and having that portion of the shank adjacent the head of square cross-section whereby said bolts will not turn, when nuts 14 are tightened upon the bolts 12 adjacent the inner face of the wall 11. The construction is such that it can only be removed from the trunk door when the same is open.

10. The body portion 9 is provided with two spaced transverse apertures 15 and 16 and corresponding apertures 17 and 18 are provided in the body portion 8 for the slidable reception of the two arms of the U-shaped retaining member 10. The body portion 9 is additionally provided with an aperture 19 which is adapted to receive the barrel 20 of a conventional-type tumbler lock which is adapted to be operated by key 21.

A bar 22, provided with three slots, 23, 24 and 25, is slidably mounted upon the inner face of the body portion 9, said bar being retained upon the member 9 by means of screw 26, the shank of which passes through slot 24. An elongated plate 27, having an upturned lug 28 and a forked opposite end is positioned upon bar 22 and is rigidly anchored to member 9 by means of the screw 26. An upstanding pin 29 is carried upon bar 22 and is positioned between the arms of the forked end of the plate 27. A coil spring 30 is anchored at opposite ends to lug 28 and pin 29 and normally urges bar 22 to the left (Fig. 2).

Each arm of the U-shaped retaining member 10 is provided with a notch 31 which is defined by tapered walls on one side and flat walls on the other side in ratchet-fashion. When the notches are disposed in alignment with the plane of the bar 22, said bar, unless otherwise restrained as will be hereinafter more fully described, will so move under the influence of spring 30 so as to engage the defining edges of the slots 23 and 25 in the notches 31, as illustrated in Fig. 2. In this position the U-shaped member 10 may be moved inwardly with respect to the trunk compartment but cannot be moved outwardly beyond the position where the bar 22 engages the notches 31.

A cam plate 32 is secured to the rotatable portion of the lock 20 by means of screw 33 and is adapted to be rotated by rotation of the key 21. The cam plate is substantially oval in shape and is adapted, when the major axis of the oval is coincident with the longitudinal axis of the bar 22, to move said bar in opposition to the tension of spring 30 and thereby move said bar so as to disengage the same from the notches 23 and 25. Rotation of the key 21 which positions the

cam plate with its minor axis coincident with the axis of the bar 22 permits the bar to be movable under the influence of spring 30 until the defining edges of the slots 23 and 25 abut the arms of the U-shaped member.

The U-shaped retaining member comprises an arm 34 which is adapted to enter apertures 16 and 18, and an arm 35 which is adapted to enter apertures 15 and 17. An extension 36 is pivotally connected, as at 37, to the end of arm 35 permitting arms 34 and 35 to be completely retracted from both pairs of apertures 16 and 18 and 15 and 17. When this condition occurs, as will be herein-after more fully described, the extension 36 will still be retained in the apertures 15 and 17, as shown best in dotted lines in Figs. 2 and 3.

A sleeve 38 is positioned in aperture 17 and extends inwardly from the body portion 8 and through the wall 11 of the trunk door 2. Inferiorly of the wall portion 11, the sleeve 38 is provided with a longitudinal slot 39 and adjacent the inner face of the wall 11, said slot extends transversely throughout approximately one-half the diameter of the sleeve, as shown best at 40 in Fig. 2. A pin 41 is carried adjacent the end of the extension 36 and projects transversely outwardly therefrom, said pin being adapted to move in slot 39 when the U-shaped member is moved outwardly or inwardly, pin 41 being further adapted to prevent undue rotation of the extension during a major portion of its longitudinal movement. Adjacent slot 40, however, the extension may be rotated throughout substantially 180° but at this portion of travel of the U-shaped member, further outward movement is prevented by pin 41.

In the use of my invention herein specifically described, the lock structure 1 is mounted upon the trunk door 2 immediately beneath the conventional trunk door lock 3. In this type of trunk door lock, the trunk door may be locked thereby turning the handle downwardly and by means of a key (not shown) turning the tumbler 6 to locking position. The lock structure 1 is so disposed with respect to the lock structure 3 that when the handle 5 is in locked position it will extend through the center of the loop formed by the U-shaped member 10.

To accommodate the movement of the handle 5 to locking position, the lock 1 may be unlocked thus moving the bar 22 to a position wherein the notches 31 are not engageable with the bar. The U-shaped member may then be moved outwardly to the position shown in dotted lines in Fig. 2 wherein the end of the arm 34 leaves the aperture 16 and the pivot 31 is moved exteriorly of the body member 9. In this position the pin 41 will abut the inner face of the wall 11 and will prevent the complete removal of the extension 36 from the lock body. The U-shaped member may then be swung about the pivot 37 thereby providing room for the handle 5 to be moved to locking position.

To lock the handle the reverse procedure is followed and the U-shaped member is moved inwardly with the loop embracing the handle 5, the tumbler of lock 20 being previously rotated to permit the defining edges of the slots 23 and 25 to bear against the arms 34 and 35 until said edges move into notches 31 under the influence of spring 30. In this position the swingable movement of the handle is restricted by the loop of the U-shaped member. In view of the fact that there is insufficient space between the han-

dle and the arms of the U-shaped member to turn the handle until its "play" is taken up, it is substantially impossible to shear the locking mechanism of the lock 3.

5 It is to be understood that the door 2 may contemplate substantially any type of swingable door or closure, such as, a refrigerator door, the usual house door, truck or railroad car door or other type of hinged closure which is provided 10 with a handle which swings in a plane substantially parallel to the plane of the closure.

In addition, my invention contemplates the mounting of the lock structure 1 upon the door frame adjacent the door where the swingable 15 door handle may protrude beyond the edge of the door. Further, my invention also contemplates the arrangement wherein a swingable bar, which swings in a plane substantially parallel to the plane of the door or closure and wherein 20 the lock structure 1 is carried upon the door or closure and wherein the swingable bar protrudes beyond the edge of the door to a position engageable with the loop of the U-shaped member.

One of the important features of my lock structure 1 in any of the combinations hereinbefore described resides in the substantially universal movement of the loop of the U-shaped member which permits its use in numerous cramped relationships with a swingable bar or 30 handle the position of which latter may leave little space for engagement. Another important feature of my lock structure resides in the fact that it is substantially self-contained and may be added to existing swingable handle installations such as found on present day motor car trunks without altering or changing the operation of the existing handle.

I claim as my invention:

In a lock for use with a swingable closure provided with a latch and a handle swingably mounted upon said closure to operate the latch, said lock being adapted for mounting upon the surface of said closure adjacent the path of movement of said handle and comprising a body, a U-shaped member slidably positioned in said body and extending substantially perpendicularly to the closure, a portion of said member being adapted to project through said closure, means for locking the U-shaped member with the loop portion thereof positioned for embracing a portion of said handle to prevent movement of the latter, an extension pivotally connected to the end of one of the arms of said U-shaped member, a sleeve extending inwardly of said body and providing a guide support for the extension and portion of said one arm, said sleeve having a longitudinally extending slot and a transverse slot intersecting the longitudinal slot adjacent said body, and a pin on the free end of said one arm disposed in said slots whereby said longitudinal slot and said pin serve to confine said U-shaped member for movement in a direction perpendicular to the closure for a predetermined distance until the pin registers with the transverse slot at which position said member is permitted to be rotated about the pivot connection of said one arm and extension to dispose the other arm out of the path of swinging movement of the handle to permit movement of the latter, and the member together with the extension in such position of adjustment also being rotatable about the axis of the extension.
